SAFETY DEVICE FOR BRAKE RODS

Edwin G. Busse, Chicago, Ill., assignor to Chicago Railway Equipment Company, Chicago, Ill., a corporation of Illinois

Application December 21, 1931, Serial No. 582,454

16 Claims. (Cl. 188—210)

This invention relates to railway rolling stock and consists in a novel safety guard for brake bottom connections.

The main object of the invention is to provide 5 a simple and efficient bottom connection safety guard which is associated with the means for securing a brake beam guard, guide or supporting strap to a truck part.

Another object is to provide means for yield- 10 ingly resisting rotation of the bottom rod guard and which tends to return the guard to its normal position in case the guard is struck and tilted by an obstacle between the rails.

These objects and others are attained by the 15 structures illustrated in the accompanying drawings, in which—

Figure 1 is a perspective view showing portions of a railway truck and brake rigging.

Figure 2 is a detail view showing a modified 20 bracket for securing the guard, guide or supporting strap to the spring plank.

Figure 3 is a view of a modification of the bottom rod guard.

Figure 4 is a detail vertical transverse section 25 through the spring plank and showing another modification of the guard.

Figure 5 is a vertical longitudinal section through the guard, guide or supporting strap and illustrating another form of bottom rod guard.

Figure 6 is a detail view corresponding to Figure 5, but showing the bottom rod guard in tilted position.

Figure 7 illustrates another modification.

Figure 8 illustrates still another modification. 30

In Figure 1, a spring plank 1 of usual channel form has a bracket 2 secured to the lower surface thereof by means of rivets 3. The bracket has a recessed top web 4 and depending flanges 5 having holes 6 receiving pins 7 which detachably 35 secure the brake beam guard, guide or support strap 8 to the bracket. The brake rigging illustrated comprises a truss-type brake beam including compression and tension members 9 and 10 and a strut 11 pivoted to brake lever 12, the 40 brake lever being pinned at the bottom to a bottom connecting rod 13. Ears 14 on the front end of strut 11 mount a chair 14a which engages strap 8.

Each pin 7 includes a hooked portion 15 de- 45 pending from the bracket 2 and extending beneath the adjacent bottom connection 13 and forming a safety guard for the bottom connection.

In Figure 2, the spring plank 17 has depre- 50 sions 18 in the horizontal web which are per-

forated to receive the legs of one or more inverted U-shaped brackets 19. The brake beam guard, guide or supporting strap 16 is secured between the legs of bracket 19 by pins 20, each having a hole 21 at one end for a cotter 60 key, and a hooked portion 22 at the other end extending beneath the bottom connection 23 and forming a safety guard therefor.

In Figure 3, pin 24 has one end extending between the flanges 25 of the brake beam guard, guide or support bracket 26, a depending side- 65 wardly disposed portion 27 extending beneath the bottom rod 28, and a flattened portion 29 at the other end secured to spring plank 30 by a rivet or bolt 31. In this form the bottom rod safety guard is more securely fastened and is more rigid than those illustrated in Figures 1 and 2, and, in case of loss of a brake lever pin, the bracket 26 is relieved of much of the weight of the connecting rod. The end of the 70 loop 27 may be hooked over the upright flange of the spring plank, as indicated at 46 in Figure 4. This form of engagement of the safety guard with the spring plank facilitates assembly and disassembly in case parts of the brake rigging or the guard, itself, are replaced. The loop 32 may be further secured to the spring plank 33 by a bolt or rivet, if desired, the latter being indicated at 34.

In Figures 5 and 6, the resilient guard, guide 75 or supporting strap 35 is slightly distorted in assembling with bracket 36 in order to prevent rattling. Pin 37 has a flattened surface 38 (see Figure 6) between the flanges of bracket 36 for engaging strap 35. The yielding pressure of the 80 strap 35 against this flattened surface increases the resistance of the pin to rotation. Moreover, if the looped end portion 40 of the pin is struck by an obstacle in the track and tilted, as shown in Figure 6, the pin will tend to return immediately to its normal position.

In Figure 7, a guard, guide or supporting strap 41 is detachably secured to a wrought type of supporting bracket 42 by a straight pin 43. The pin at the head end mounts a bent 85 strap or loop 44 which extends beneath the bottom connection 45 and is secured to spring plank 39 by a rivet 50.

In Figure 8, the pin 47 has a closed loop 48 at one end which encircles the bottom connection 49. The pin could be squared at the head end and a separate loop provided, similar to the element 44 in Figure 7.

In each of the figures, the brake beam guard, 105 guide or support members illustrated and their 110

supporting brackets are of the types now generally in use, and in each of the forms, except that shown in Figure 7, the looped pin replaces the pin ordinarily used to detachably secure the 5 brake beam guard, guide or support member to the bracket. This bracket might be secured to, or formed integral with, a truck member other than the spring plank, such as the bolster, a convenient transom, or an arm on the side 10 frame. The device has fewer parts than other devices at present used for accomplishing a similar purpose and is, accordingly, less expensive and more durable.

Obviously, various details of the structures 15 illustrated might be varied within the spirit of the invention and the exclusive use of all such variations as come within the scope of the appended claims is contemplated.

What is claimed is:

20 1. In combination, a railway truck part, flanges on said part, brake rigging including a bottom connection, a brake beam guard, guide or support member mounted between said flanges, and a pin-like element extending between said flanges and securing said member to said part, said element having an end portion extending beneath said connection and safeguarding the same.

25 2. A device for detachably securing a brake beam guard, guide or support strap to a truck part and including a movable pin having a depending hooked portion for safeguarding a brake bottom connection.

30 3. In combination, a railway truck part, a bracket on said part for mounting a brake beam guard, guide or support member, and a pin for securing said member in said bracket and having an end portion projecting beyond said bracket and forming a safeguard for a brake bottom connection.

35 4. In combination, a railway truck part, a bracket on said part for mounting a brake beam guard, guide or support member, a pin-like element for securing said member in said bracket, and structure carried solely by said element and disposed to form a safeguard for an adjacent brake bottom connection to prevent the connection from falling to the track upon failure of the lever attaching pin.

40 5. In combination, a railway truck part, a bracket on said part for mounting a brake beam guard, guide or support device, and a member for securing said device in said bracket and having an offset portion projecting beyond said bracket and forming a safeguard for a brake bottom connection, said member having a flat surface engaging said device to resist rotation of said member.

45 6. A pin for securing a brake beam guard, guide or support member to a supporting bracket and having a portion with a flat surface for engaging the guard, guide or support member to resist rotation of the pin, and having an end part offset from said portion and arranged to underlie and safeguard a brake bottom connection.

50 7. In combination, a railway truck part having depending flanges, a resilient brake beam guard, guide or support member mounted between said flanges, and a pin extending between said flanges and securing said member to said part, said pin having a flattened portion engaging said member and having a swingable part

projecting beyond said bracket and disposed to underlie a brake bottom connection, said member yieldingly bearing against said flattened portion whereby the resistance of said pin to rotation is increased and said pin will be returned to its normal position in case said depending portion is tilted.

8. In a railway truck, a transverse part, flanges depending therefrom, a brake beam guard, guide or support member mounted between said flanges, and a pin extending between said flanges and detachably securing said member to said part, said pin having a hooked end portion extending outwardly from said flanges and then upwardly and engaging said part to form a loop for safeguarding a brake bottom connection.

9. In a railway truck, a part having projecting flanges, a brake beam guard, guide or support device mounted between said flanges, a member extending between said flanges and detachably securing said device to said part, and structure projecting from an end of said member and extending sidewardly and then upwardly and engaging said part, said structure forming a loop for safeguarding a brake bottom connection.

10. In combination, a railway truck member, a brake beam guard, guide or support member, said members being yieldingly associated, and a bottom rod guard device supported by one of said members and with a flat surface engaging the other member for resisting rotation of said device.

11. In combination, a railway truck member, a brake beam guard, guide or support member carried by said truck member, one of said members being resiliently supported relative to the other, and a brake rigging safety guard device rotatable relative to said members and with a flattened surface engaging one of said members to yieldingly resist rotation of said device.

12. In combination, a railway truck part, a brake beam guard, guide or support bracket carried thereby and having spaced flanges, and a bottom rod guard pivotally secured to and solely supported by said flanges.

13. In combination, a railway truck part, a brake beam guard, guide or support device secured thereto, and a bottom rod guard pivotally secured to said device and solely supported thereby.

14. In combination, a brake beam guard, guide or support device, a brake rod guard movably carried by said device, and means yieldingly stabilizing said rod guard in the normal position thereof.

15. In combination, a brake beam guard, guide or support device including a part for attaching the device to a main support, a brake rod guard swingably carried by said part, and means yieldingly resisting swinging of said rod guard in the normal position thereof, said means providing substantially less resistance to the swinging of said rod guard when said rod guard is out of said normal position.

16. In combination, a railway truck part, flanges projecting therefrom, a brake beam guard, guide or support member between said flanges, a pin-like element extending between said flanges and securing said member to said part, and a brake rod guard structure carried by said element and said part.

EDWIN G. BUSSE.
